UNITED STATES PATENT OFFICE.

JAMES PRINCE, OF LOS ANGELES, CALIFORNIA.

INKING MECHANISM FOR PRINTING-PRESSES.

1,130,334.

Specification of Letters Patent.

Patented Mar. 2, 1915.

Application filed April 13, 1914. Serial No. 831,391.

To all whom it may concern:

Be it known that I, JAMES PRINCE, a citizen of the United States, residing at the city of Los Angeles, in the county of Los

5 Angeles and State of California, have invented new and useful Improvements in Inking Mechanism for Printing-PresSES, of which the following is a specification.

My invention relates to that class of 10 presses known to the trade as Gordon presses.

Heretofore such presses have been provided with what is known as disk distribution for the ink over which the form rollers 15 were passed to obtain a supply of ink for the form and great difficulty has been experienced in inking the form thoroughly and evenly owing to the fact that the form rollers do not have proper contact with the 20 disk, which renders this class of presses useless for printing the best class of work.

It is the object of my invention to provide inking means for presses of this character which will obviate the above named 25 objections and which will enable this class of press to be used for the best class of work thus doing away with the expense of having special machinery for that purpose.

A further object is to provide a device of 30 this character which will be simple in construction and operation, easily and quickly attached to any standard form of press without materially changing the same.

I accomplish these objects by the mechanism described herein and illustrated in the accompanying drawings forming a part hereof in which:

Figure 1 is a side elevation of so much 40 of a machine as will illustrate my invention. Fig. 2 is a diagrammatic rear view of the operating mechanism of Fig. 1. Fig. 3 is an enlarged side elevation of my attachment removed from the machine. Fig. 4 is a top plan of Fig. 3, with parts omitted. Figs. 5 45 and 6 are details of the ink fountain and its operative parts. Fig. 7 is a sectional detail of the connection between the telescopic shafts. Fig. 8 is a sectional detail of the ink fountain with one of the sides 50 removed.

My device comprises two side plates 10 and 11 at the lower portions of which are provided lugs 12 which extend inwardly and provide means for attachment to the frame 55 13 of the machine. An inking cylinder 14 is rigidly mounted upon shaft 15, the ends

of which are rotatably mounted in bearings in side plates 10 and 11 and project a short distance above the top of said side plates.

At the rear of cylinder 14 and in contact with the periphery thereof are mounted composition rollers 16 and 17. Rollers 16 and 17 have their ends journaled in slots 18 and 19 in side plates 10 and 11. A vibrating distributing roller 20 of ordinary construction has its ends 21 mounted in slot 19 at the rear of roller 17 and has its periphery in contact with the peripheries of rollers 16 and 17. Set screws or other suitable means 70 are provided for adjusting the ink and vibrating rollers. An ink fountain 22 of ordinary construction is bolted or otherwise secured to plates 10 and 11 at the lower ends of the rear edges thereof and is provided 75 with the usual feed roll 23 rigidly mounted on shaft 24 the ends of which are revolvably mounted in bearings in the sides of the ink fountain 22. Shaft 24 has mounted on one of its ends, near the inner wall of one side 80 of the ink fountain, a ratchet wheel 25 which is operated by a pawl 26 mounted on operating lever 27. A ductor roller 28 is revolvably mounted in bearings on the free end of rocking levers 30 and 31 and normally rests upon the upper side of feed roll 23. The other ends of levers 30 and 31 are rigidly mounted upon a rock shaft 32 which shaft is journaled in plates 10 and 11. An operating arm 33 has one end rigidly secured to the under side of rocking lever 31 and extends rearwardly and then downwardly a short distance.

Secured upon the outer end of the operating shaft 34 of the machine is a miter gear 95 35 which meshes with a miter pinion 36 secured upon the lower end of a hollow shaft 37. The lower end of shaft 37 is revolvably mounted in a swinging bearing 38. Bearing 38 is connected by arm 39 to a tubular collar 100 40 loosely mounted upon shaft 34 near the inner side of gear 35. An operating shaft 41 is slidably mounted within hollow shaft 37 and extends upwardly and has mounted upon the upper end thereof a bevel gear 42 105 which meshes with a similar gear 43 secured upon the outer end of a horizontal stub shaft 44. Shaft 41 is supported at its upper end in a bearing 45 which bearing is connected by arm 46 to a tubular collar 47 loosely 110 mounted upon shaft 44 near the inner side of gear 43. Shaft 44 is mounted at or near

its inner end in a bearing 48 secured to the top of the outer side of side plate 10. Bevel gears 49 and 50 connect the inner end of shaft 44 and the upper end of a vertical stub shaft 51. Shaft 51 is revolvably mounted in a bearing 52 secured upon the inner side of plate 10 and has secured upon the lower end thereof a bevel gear 53 which meshes with a similar gear 54 secured upon the end of shaft 15 of the ink roller 14 and rotates the same. A key 55 is secured within hollow shaft 37 at the upper end thereof and registers with a spline 56 cut in operating shaft 41. This construction is best shown in Figs. 2 and 7 and permits shaft 41 to slide within shaft 37 but provides that said shafts shall rotate in unison.

In operation as the machine is operated in the usual manner gear 35 will be rotated with shaft 34 and will by means of the gearing connected thereto cause inking roller 14 to be rotated as long as the machine is being run. As the form roller frames 57 are oscillated the bar 58 connecting ends thereof will on its upward travel engage the end of feed roller operating lever 27 and the end of operating arm 33 of the ductor roller and carry the same upwardly. This movement will cause the ductor roller to be brought up into contact with vibrating roller 29 and as said vibrating roller is being rotated continuously by inking cylinder 14 and the composition rollers this contact will cause the ductor roll to be rotated and will spread ink therefrom upon the vibrating roller from which it is transferred to the composition rollers and then on to the inking cylinder. As operating lever 27 is raised said lever raises pawl 26 to a position where it engages a tooth in ratchet wheel 25 and upon the downward movement of the bar 58 a lug 59 secured to the lower edge of the inner side thereof will engage the lower end of rod 60 the upper end of which is secured to the outer end of lever 27, and draw said lever downwardly to its normal position. This movement rotates feed roller 23 and ductor roller 28 resting upon the upper side thereof will also be rotated and will be coated with ink. The ductor roller returns to its normal position by gravity as soon as bar 58 releases the end of operating arm 33.

By this construction I have provided a cheap, simple and efficient means for inking the form of printing presses which will render the press more efficient.

Having described my invention what I claim is:

1. In a platen printing press mechanism comprising a frame secured to the frame of the press; an inking cylinder revolvably mounted in said frame; composition rollers

adjustably mounted in said frame having their peripheries adapted to be brought into contact with the periphery of the inking cylinder; a vibrating distributing roller contacting with the peripheries of said composition rollers and connecting the same rotatably mounted in said frame; an ink fountain; a feed roll revolvably mounted in said fountain; a ductor roller revolvably mounted in said frame to oscillate between said feed roll and the vibrating roller; means to operate said feed and ductor roller; and means to rotate said inking cylinder comprising an oscillating telescopic shaft operatively connecting said inking cylinder and the driving shaft of the press.

2. The combination with a Gordon press of an inking device comprising a frame bolted to the side arms of the machine; an inking cylinder for the form rollers revolvably mounted in said frame; distributing rollers mounted in said frame in contact with said inking roller and spaced apart; a vibrating roller contacting with said distributing rollers and connecting the same mounted in said frame to rotate therein; an ink fountain secured to said frame; a feed roller revolvably mounted in said ink fountain; a transfer roller mounted in said frame to oscillate between said feed and vibrating rollers; a telescopic connection between the inking cylinder and the driving shaft of the press for revolving the cylinder; means for intermittently oscillating said transfer roller; and means for intermittently revolving the feed roller.

3. An inking device for a press of the Gordon type comprising a frame; an inking cylinder mounted in said frame to rotate therein; distributing rollers adjustably and revolvably mounted in said frame in contact with said inking cylinder; a vibrating roller contacting with said distributing rollers adjustably and revolvably mounted in said frame; an ink fountain; a feed roller revolvably mounted in said ink fountain; a transfer roller mounted in said frame to oscillate between the feed roller and the vibrating roller; an oscillating telescopic connection from said inking cylinder to the driving shaft of the press; means to cause said transfer roller to contact first with the feed roller and then with the vibrating roller; and means to intermittently rotate said feed roller.

In witness that I claim the foregoing I have hereunto subscribed my name this 6th day of April, 1914.

JAMES PRINCE.
